ELECTRIC SWITCH ASSEMBLY

Kenneth C. Allison, Crystal Lake, and Edward P. Herrick, Palatine, Ill., assignors to Grigsby-Allison Company, Inc., Arlington Heights, Ill., a corporation of Illinois

Application June 2, 1947, Serial No. 751,674

6 Claims. (Cl. 200—6)

1.

This invention relates to improvements in an electric switch assembly.

Objects of this invention are simplicity of construction, durability, reliability, inexpensiveness of manufacture and other objects and advantages which will hereinafter appear.

In the accompanying drawing,

Fig. 1 is a view, partly in vertical section and partly in elevation, of a switch constructed in accordance with this invention showing the manner in which the contacts are positioned when in circuit-open position.

Fig. 2 is a top plan view of the switch shown in Fig. 1.

Fig. 3 is a fragmentary elevational view similar to Fig. 1 but showing the manner in which the contacts are separated for interruption of the circuit to be controlled thereby.

Fig. 4 is a downward sectional view taken on line 4—4 of Fig. 1.

Fig. 5 is an upward sectional view taken on line 5—5 of Fig. 1.

Fig. 6 is a downward sectional view taken on line 6—6 of Fig. 1.

Referring to the drawing, the present switch includes a front plate 10 having parallel arms 11 at opposite edges thereof which extend therefrom at substantially right angles to the plane of the plate 10. Bridging the space between said arms 11 of the plate 10 and mounted in spaced parallel relation to the plate 10 is a plate 12 provided with ears 13 at opposite edges thereof having openings 14 in alignment with and adapted to receive the reduced outer ends of the arms 11 therethrough. Arms 15 formed at peripherally spaced locations on the edge of the plate 12 and extending in the direction of the front plate 10 are provided with reduced end portions which engage aligned notches 20 formed in the edge of an insulating base 21, which end portions are bent into engagement with the remote face of the base 21 whereby the latter is rigidly supported at a fixed distance from and parallel to the plate 12.

An externally threaded sleeve or bushing 22^a is fastened at one end to the edge of a suitable opening formed centrally of the front plate 10, from which the sleeve 22^a extends away from the space between the plates 12 and 21. An operating shaft 22 is supported for rotation in the sleeve 22^a. A C-washer 23 keyed to a groove 24 in one end of the shaft is engaged by the outermost edge of the bushing 22^a so as to position the opposite end of the shaft, having flattened sides 25, at a fixed distance beyond the insulating base 21 and

2.

the plate 12, the latter having central openings in which said end of the shaft has free turning movement.

Interposed between the plate 12 and the insulating base 21 is an insulating disk 26 provided with a central opening 27 with the edges of which the flattened sides 25 of the shaft 22 have driving engagement. Thus the shaft 22 and disk 26 rotate in unison while the disk 26 has limited axial movement relative to the shaft in the space between the insulating base 21 and the plate 12. Pressing against the disk 26 and acting to urge the latter in the direction of the plate 12 is the outwardly sprung end of a resilient contact 41 secured as at 42 to the insulating base 21 and having a perforated terminal portion projecting beyond the periphery of the base 21 to facilitate attachment of circuit wires. A stationary contact 43 secured as at 44 to the base 21, also provided with a terminal portion in the same manner as contact 41, is arranged to be overlapped by the outwardly sprung end of said contact 41. The disk 26 is provided with a notch 45 in the edge thereof and a diametrically opposite recess 46, which recess and notch are adapted to register with conical projections 47 and 48, respectively formed in and extending from the face of the plate 12 opposite the disk 26 in one rotated position of the shaft 22 and disk 26. In such position of the disk relative to the plate 12, the disk 26 is permitted to move toward the plate 12 a distance sufficient to accommodate movement of the resilient contact 41 out of engagement with the stationary contact 43, overlapped thereby. When the disk 26 is rotated by the shaft 22 to a position wherein the notch and recess are out of registry with the projections 47 and 48, the disk will contact with the projections 47 and 48 as a cam to press the resilient contact 41 into engagement with the contact 43 to close the circuit through said contacts.

As shown in Figs. 1 and 2, the shaft 22 and the reduced ends of the arms 11 of the front plate 10, may be of such length as to provide a mounting for an auxiliary or tandem switch comprising contact arms 50 secured to a rotor 49 supported for turning movement with the shaft 22 to engage selected contacts 51 and 52 arranged circularly on a stationary insulating base 53 secured to the arms 11. The base 53, as shown, is supported in spaced parallel relation to the front plate 10 by means of a spacer 54 constituting a strip of material which is sheared and stamped inwardly of its edges to provide alternating oppositely offset vertical sections 55 whose inner

surfaces define a passage through which the ends of the arms 11 project for attachment to the member 53 by staking or other suitable means.

Rotated positions of the shaft 22 and the disk 26 and the rotor 49 are indexed or located to coincide with the operation of the contacts 41 and 42 on the insulating base 21 and the contacts 50, 51 and 52 by means of a spring disk 66 staked to the shaft 22 as at 67 and provided with a tail 70 engageable with suitable stops on the plate 10, such as a lug 68 and the edge of one of the arms 11.

As clearly illustrated in Figs. 4 and 5, the opening in the disk 26 is of hour glass periphery so as to afford a slight lost motion between the disk 26 and the operating shaft 22 whereby the disk may finish each of its circuit opening or closing movements with a snap action.

The present invention accordingly affords a novel and improved construction of rotary switch having contacts which are normally biased to open circuit position together with simple and efficient means for effecting control of such contacts. It is also apparent that the present invention provides novel means for providing tandem mounting of a plurality of switches combined for control by a common operating element therefor.

It will be understood that the switch construction of the present invention may be embodied in various types of plural switch assemblies other than that illustrated and described, and that changes may be made therein within the spirit and scope thereof as defined in the appended claims.

What is claimed is:

1. An electric switch comprising a pair of spaced, rigidly connected plates, a flat disk of insulating material interposed between said plates and adapted to seat against the surface of one of said plates, a pair of contacts secured to the other of said plates and facing said disk, one of said contacts comprising a resilient arm whose free end overlies and is biased out of engagement with the other contact, cooperating means on the disk and the plate against which the disk is adapted to seat for applying pressure on said resilient arm through said disk to move said arm into engagement with the other contact in a selected rotary position of said disk, so accommodating said disk in another rotary position as to release said resilient arm for movement of the latter out of engagement with said contact, and means for rotating said disk including a rotating operating shaft on which said disk is supported for relative axial movement.

2. An electric switch as defined in claim 1 wherein said cooperating means on the disk and the plate against which the disk is adapted to seat comprises projections formed in and extending from transversely opposed surface portions of said plate opposite said disk, and recesses formed in said disk adapted to register with and accommodate said projections.

3. An electric switch as defined in claim 1

wherein said cooperating means on the disk and the plate against which the disk is adapted to seat comprises conical projections formed in and extending from transversely opposed surface portions of said plate opposite said disk, and recesses formed in said disk adapted to register with and accommodate said projections.

4. An electric switch comprising a pair of plates, means for supporting said plates in fixed assembly including a member having parallel arms at opposite edges thereof between which said plates are arranged in spaced apart relation lengthwise of and intermediate the opposite ends of said arms, a flat disk of insulating material interposed between said plates and adapted to seat against the surface of one of said plates, a pair of contacts secured to the other of said plates and yieldably urging said disk toward a seated position as aforesaid, one of said contacts comprising a resilient arm whose free end overlies and is normally biased out of engagement with the other contact, cooperating means on the disk and plate against which the disk is urged to seat by said resilient arm for applying pressure on the latter through said disk to move said arm into engagement with the other contact in a selected rotary position of said disk and so accommodating said disk in another rotary position as to release said resilient arm for movement of the latter out of engagement with said contact, aligned openings in said supporting member, plates and disk, a bearing extending outwardly from and secured to the edges of the opening in said supporting member, means for rotating said disk including an operating shaft rotatably mounted in said bearing and extending through said openings in said supporting member, plates and disk.

5. An electric switch as defined in claim 4 wherein said shaft extends beyond said plates a distance substantially coextensive with the outer limits of said arms of the supporting member, and an insulating base fixed between the outer limits of said arms is provided with circularly arranged contacts which cooperate with contacts provided on a rotor operatively connected with the outer end of the shaft.

6. An electric switch as defined in claim 4 wherein said cooperating means on the disk and the plate against which the disk is adapted to seat comprises projections formed in and extending from transversely opposed surface portions of said plate opposite said disk, and recesses formed in said disk adapted to register with and accommodate said projections.
